US00D784322S

(12) **United States Design Patent** (10) Patent No.: **US D784,322 S**
(45) Date of Patent: **** Apr. 18, 2017**

(54) **ELECTRONIC DEVICE**

- (71) Applicant: **Samsung Electronics Co., Ltd.**, Suwon-si (KR)
- (72) Inventors: **Nam-Su Kim**, Seoul (KR); **Do-Hyung Ha**, Gwangmyeong-si (KR); **Sae-Hee Lee**, Incheon (KR); **Hyun-Sook Kim**, Seoul (KR)
- (73) Assignee: **Samsung Electronics Co., Ltd.**, Suwon-si (KR)
- (**) Term: **14 Years**
- (21) Appl. No.: **29/504,686**
- (22) Filed: **Oct. 8, 2014**

Related U.S. Application Data

- (63) Continuation-in-part of application No. 29/504,020, filed on Oct. 1, 2014.

(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures show portions of the electronic device which form no part of the claimed design.

1 Claim, 6 Drawing Sheets
